UNITED STATES PATENT OFFICE.

JOHN FROELICH, OF ST. PAUL, MINNESOTA, ASSIGNOR TO LESLIE S. HACKNEY, OF ST. PAUL, MINNESOTA.

CIRCULAR RADIATOR.

1,390,899.

Specification of Letters Patent. Patented Sept. 13, 1921.

Application filed July 16, 1918. Serial No. 245,183.

To all whom it may concern:

Be it known that I, JOHN FROELICH, a citizen of the United States, resident of St. Paul, county of Ramsey, State of Minnesota, have 5 invented certain new and useful Improvements in Circular Radiators, of which the following is a specification.

The object of my invention is to provide a water-cooling radiator for internal combustion engines which will be simple and compact in construction and at the same 10 time have a very large radiating surface.

A further object is to provide a radiator which will stand the vibration to which a 15 radiator for this purpose is subjected without danger of leakage, a very decided objection to tractor radiators as usually constructed.

A further object is to provide a radiator of 20 a particularly convenient form for tractors where the crank shaft of the motor lies crosswise of the frame. In such case it is decidedly inconvenient to belt to a fan of the ordinary type of radiator, while in my im- 25 proved construction this can be easily done.

Other objects of the invention will appear from the following detailed description.

The invention consists generally in various 30 constructions and combinations, all as hereinafter described and particularly pointed out in the claims.

In the accompanying drawings forming part of this specification,

Figure 1 is a vertical sectional view 35 through a circular radiator embodying my invention,

Fig. 2 is an elevation of the receiving end 40 of the radiator, with a portion of its end wall broken away to show the circulating tubes,

Fig. 3 is a similar view of the discharge end of the radiator.

In the drawing, 2 represents a suitable base, secured to the frame of the tractor or other machine on which the radiator is to be 45 used, and formed integrally with said base are heads 3 and 3^a, preferably of casting. The head 3 is provided with a water intake pipe 4 at the top leading to a circulating chamber 5 and from this chamber the water 50 flows through tubes 6 to a corresponding chamber 5^a in the head 3^a, the tubes being of suitable length and supported intermediate to their ends and at the center by rings 7. The chamber 5^a communicates with a 55 chamber 9 in the head 3, separated from the

chamber 5 by a baffle wall 10, and the chamber 9 communicates through the circulation tubes with a chamber 11 in the head 3^a that is provided with an outlet pipe 12. The water entering the radiator, therefore, passes 60 through about one-third of the tubes to the head at the opposite end from the intake, then back again to the receiving head and from thence to the discharging head and chamber and out of the radiator, and thereby the water is compelled to follow a tortuous path and remain in the radiator for a considerable length of time. The heads are 65 each provided with a peripheral flange 13 and the circulating tubes are mounted in 70 plates 14 which are secured to the flanges 13 by suitable means, such as bolts 15. In manufacturing the radiator, the tubes are first mounted in the plates 14 and then the plates 75 and heads are bolted together. The heads have hubs 16 centrally arranged therein connected by spokes 17 with the outer portions 80 of the heads and in these hubs bearing boxes 18 are mounted for a shaft 19. Upon this shaft on each side a fan hub 20 is arranged. A disk 20' is mounted on the hub 20 and supports the fan blades 20''. This fan is of 85 the multi-vane type, with both ends open and air is admitted through the openings in the heads at both ends of the radiator and blown out between the cooling tubes, and the tubes are so mounted that the currents of air will be compelled to follow a zigzag course between them and contacting with the surfaces of the tubes, will cool the walls 90 thereof and reduce the temperature of the water flowing through the tubes, and as the water is passed back and forth from one end of the radiator to the other, it is subjected to the cooling air currents for a considerable period of time, sufficient at least 95 to keep the water at the desired temperature.

A radiator built in this way will not only be thoroughly practical and efficient as a cooling means for the water circulating system, but will be extremely durable under the adverse conditions of operating a tractor, where vibration is such that a radiator as ordinarily constructed will soon become racked and twisted to such an extent that it 100 will leak and cannot be easily repaired or kept in good order. Furthermore, this radiator can be easily belted to a crank shaft that is mounted crosswise to the frame of the machine.

I have described this liquid cooling radiator for use in connection with a tractor, but it will be understood that it is equally applicable in various ways where the rapid 5 cooling of a liquid is desired, hence I do not confine myself to the particular use hereinbefore described.

I claim as my invention:

1. A water cooling radiator comprising 10 heads, one having an intake pipe and the other a discharge pipe, a series of water circulating tubes connecting chambers provided in said heads and baffle walls provided in said heads and separating said 15 chambers into independent compartments and directing the flow of water back and forth through said tubes between said heads, and a fan encircled by said tubes for establishing currents of air outwardly between 20 said tubes.
2. A water cooling radiator comprising 25 heads having chambers formed therein and supply and discharge pipes for said heads, plates secured to said heads and forming the inner walls of said chamber, circulating tubes mounted in said plates and forming 30 communicating passages between the opposite chambers in said heads, means for dividing the chambers in each head into separate compartments and compelling the water to flow back and forth through groups of said tubes from one head to the other between said inlet and outlet pipes, and a blast fan encircled by said tubes for directing 35 currents of air outwardly between them.
3. A water cooling radiator comprising 40 ring-shaped heads having intake and discharge pipes respectively, said heads having hubs and spokes connecting said hubs with the outer portions of said heads, said heads having water-circulating chambers formed therein, each divided into a plurality of compartments, circulating tubes

connecting the opposite compartments of said chambers for conducting the water to 45 be cooled back and forth from one head to the other, a centrally arranged partition supporting said tubes intermediate to said heads, a shaft journaled in said hubs and fans mounted on said shaft upon each side 50 of said partition for establishing currents of air inwardly through the open ends of said heads and outwardly between said circulating tubes.

4. A water cooling radiator for internal 55 combustion engines cylindrical, substantially, in form, comprising heads and water circulating tubes between them, said heads having intake and discharge ports respectively, a cylindrical fan arranged within 60 said radiator and encircled by said tubes and having its longitudinal axis parallel substantially with said tubes, said heads having openings therein for admitting incoming currents of air to the blades of said 65 fan and said currents of air being forced outwardly by said blades around and between said tubes.

5. A liquid cooling radiator comprising 70 heads at the ends of the radiator having liquid circulating chambers therein and intake and discharge pipes therefor, a series of circulating tubes having their ends mounted respectively in said heads and communicating with said chambers, said chambers having means for directing the flow of the liquid back and forth through said tubes between the opposite heads, and a cylindrical fan interposed between said heads and encircled by said circulating tubes, the revolution of said fan directing currents of air 75 outwardly through and between said tubes.

In witness whereof, I have hereunto set my hand this 3d day of July, 1918.

JOHN FROELICH.
